UNITED STATES PATENT OFFICE.

GEORGE J. BOHLMAN, OF MEDFORD, MASSACHUSETTS.

APPARATUS FOR THE MANUFACTURE OF PAPER SPOONS, &c.

1,181,964.

Specification of Letters Patent.

Patented May 2, 1916.

Application filed February 13, 1915. Serial No. 8,103.

To all whom it may concern:

Be it known that I, GEORGE J. BOHLMAN, a citizen of the United States, residing at Medford, in the county of Middlesex and 5 State of Massachusetts, have invented an Improvement in Apparatus for the Manufacture of Paper Spoons and other Articles, of which the following is a specification.

This invention relates to a method of producing a spoon such as forms the subject-matter of my application for Letters Patent No. 8,105, filed February 13, 1915, and to an improved machine adapted for the carrying out of such method to produce the 15 spoons automatically and rapidly.

The object of the invention is to produce a spoon for sampling or like purposes, of paper stock, that will be relatively strong and rigid particularly at the shank or handle portion thereof and where it joins the bowl, without requiring any separate reinforcing element, or an excess thickness of the paper stock itself.

According to my improved method the 25 spoons are produced rapidly and automatically, by softening and heating the paper which may be drawn in an endless web from a roll, cutting and forming the same, as by the use of coöperating dies, and then 30 permitting the formed spoons to cool and set; and an organized machine is here shown for carrying out said method.

Referring to the drawings: Figure 1, shows in side elevation with parts broken 35 away in section, of a machine embodying this invention. Fig. 2, is a plan view of the concave or female die employed in the production of the spoon. Fig. 3, is a perspective view showing the coöperating male 40 die. Fig. 4, is a detail section on line 4—4 of Fig. 3. Fig. 5, is a similar detail section on line 5—5 of Fig. 3. Fig. 6, is a bottom plan view of the spoon. Fig. 7, is a top plan view of the spoon, and, Fig. 8, is an 45 edge view of the spoon.

The spoon which is produced by the method and machine here shown, which is primarily though not exclusively designed for sampling or like purposes, is formed of 50 paper or like sheet pulp stock with a bowl 1, and a shank or handle 2, extending therefrom. The point of weakness in such a spoon is usually in the shank-portion of the handle and also at the point where the handle joins the bowl. To strengthen the spoon at these points the shank-portion of the

handle is of a bowed form, concave from the back as seen at 3, and this formation is continued as lateral flanges which extend forwardly a substantial distance along the 60 sides of the base of the bowl as indicated at 4; *i. e.*, these lateral flanges extend as reversed curves from the concave of the bowl well along the back portion of the bowl. Thus at the point where the handle joins 65 the bowl of the spoon indicated approximately at 5, instead of a flat section with a tendency to easy bending and distortion, the spoon presents a section with well defined lateral flanges at its sides constituting 70 ribs or struts that make the handle much stiffer and more serviceable. For producing a spoon of this form from paper stock I provide a matrix or female die 6, in a die block 7, there being a presser foot 75 or plate 8 positioned over this block and die to permit the paper to be moved thereunder. For coöperation with matrix 6, I provide a male die 9, carried by and projecting from a head 10, the mounting of which will be 80 presently further described. This die is of a substantially convex cross-section where it forms the bowl of the spoon as indicated at 11 while the portion that forms the shank or handle of the spoon is substantially concave as seen at 12. It will be understood 85 that the projecting prongs 13 of this concave formation extend along some little distance, overlapping the central convexity 90 which forms the bowl of the spoon. 90

A machine suitable for the production of the present spoon and for carrying out the present method is shown in Fig. 1, the lower matrix or die block 7, being mounted on a suitable base frame 14, and the die 9, being 95 carried by a slide head 15, guided in vertical slide-ways 16, of the frame-work and actuated by an eccentric 17 from a driving-shaft 18, suitably journaled in an upright extension of the frame-work. At one end 100 of the machine a journal bearing 19 is provided for a roll R of paper or like pulp stock of suitable thickness. A presser-roll 20, is shown as swingingly mounted to control the delivery from this paper-roll. The 105 web of paper P, as it is drawn from this roll, passes through a steam-box 21, having an inlet pipe connection 22 and a discharge-pipe 23. This box is also shown as provided with a door 24, hinged at 25, at one 110 side thereof, whereby access may be had to the box. The paper is shown as guided over

rolls 26, adjacent the ends of this box, passing through slots in the box-end and sliding shutters 27, to keep the slot-openings through which the paper passes substantially closed. The box 21 is shown as made quite long in the direction of the paper feed so that the paper may become saturated with moisture and thoroughly heated while passing therethrough at a relatively rapid rate.

10 For effecting the automatic feed of the paper, feed-rolls 28 are provided, one in advance of the die-mechanism to feed the paper thereto, and the other beyond the die-mechanism to draw along the waste from 15 which the spoons have been cut. These rolls are driven by suitable gearing 29 and pawl and ratchet mechanism 30 from a crank-arm 31 connected with the shaft 18. The two feed rolls are similar in form and similarly geared and they are connected together 20 by a rod 32, connected to their respective pawl-arms 33, so that they give equal feed-impulses to the paper. For co-operation with these feed rolls, spring-pressed backing- 25 rolls 34 may be provided as is usual. A discharge trough or chute 35 leads from a point in the path of the spoons thus died out from the paper web, just beyond the die-mechanism, and the spoons dropping 30 thereinto are discharged laterally while the scrap-web is moved forward by the feed-roll beyond, out of the way.

In operation the paper web is drawn from the roll R, by the feed-rolls operated by the 35 pawl and ratchet devices 30. It will be understood that this feeding movement is intermittent and that the connections are so arranged that the movable die 9, will descend while the web is at rest, to blank out 40 a spoon. The paper in passing through the steam-chest 21, is thoroughly saturated with moisture and also heated by the steam so that it is very soft and pliable and capable of being readily formed to shape by the dies 45 after being blanked out, to produce the described form of spoon. The die 9, in descending, first cuts or blanks out the stock to form the spoon from the web and then pressing this blanked out portion into the 50 female die perfects the spoon shape. Thereupon, as the spoons are discharged from the chute 35, they are free to cool and set without danger of distortion and without requiring any further attention. Thus the 55 spoons can be readily and cheaply produced.

While I have herein referred to spoons as the article being produced, it will be understood that this reference is merely illustrative and intended to typify any like article having similar attributes and requirements. The present embodiment is therefore not to be considered as restrictive.

It is the intention in the present invention to confine the steam with which the paper is treated in a steam-chest, instead of merely 65 delivering jets of steam across the path of paper, for when the steam is so confined, a thorough and uniform saturation and heating of the paper is insured. When the steam is not confined, but is merely delivered from 70 a jet, it quickly disseminates and does not effect a sufficient and uniform saturation and heating of the paper. A considerable advantage also results from the moistening and heating of the paper prior to its engagement by the cutting dies, instead of being 75 moistened and heated at the moment that the dies operate, as in the latter case, sufficient time does not elapse for the paper to become thoroughly and uniformly saturated 80 and heated before being cut and shaped, or molded.

I claim:

1. A machine of the character described, including a supporting structure, means for supporting a roll of paper in strip form, co-acting die-members operable for cutting blanks from the strip of paper and molding said blanks into the desired form, co-acting feeding mechanisms arranged on opposite 90 sides of the die-members, for feeding the strip of paper to the die-members, and drawing the waste material from between the die-members, a discharge trough arranged transverse to the path of the strip 95 of paper, said discharge trough being adapted to receive the molded blanks, said blanks being removed from the die-members and conveyed to the discharge chute by the forward movement of the strip of paper, 100 and means for intermittently actuating the feeding mechanisms.

2. A machine of the character described including a supporting structure, means for supporting a sheet of material, a steam chest 105 through which the sheet of material passes, the end walls of the chest having relatively narrow openings snugly receiving the sheet of material to prevent the escape of steam from the chest, co-acting dies operable for 110 cutting blanks from the material and shaping said blanks into desired form subsequent to the passage of the sheet of material through the steam chest and while it is in a temperate state, and means for feeding 115 the sheet of material as a web through the steam chest.

In testimony whereof, I have signed my name to this specification in the presence of two subscribing witnesses.

GEORGE J. BOHLMAN.
